UNITED STATES PATENT OFFICE.

HENRY L. PALMER, OF BROOKLYN, NEW YORK.

DESIGN FOR NON-CONDUCTING PLATFORM.

Specification forming part of Design No. 7,527, dated July 7, 1874; application filed May 21, 1874.
[Term of Patent 7 years.]

To all whom it may concern:

Be it known that I, HENRY L. PALMER, of Brooklyn, in the county of Kings and State of New York, have invented a Design for Non-Conducting Platforms, of which the following is a specification:

The nature of my design is fully represented in the accompanying drawing, to which reference is made.

Figure 1, in the drawing, is a top view of a non-conducting platform embodying my invention. Fig. 2 is a vertical section through the center of Fig. 1.

A A' are concentric beads or corrugations, formed as shown in Figs. 1 and 2. B B' are flat portions of the non-conducting platform, the former at the center and the latter near the outer edge of the platform. C is a return molding or bead on the extreme edge of the

platform, so formed as to conceal the sharp edge of the metal, or other material, of which the platform may be made.

The distinctive character of my design is found in the combination of concentric ornamental beads or moldings with one or more flat portions, B B', the outer edge of the board being ornamented with a return bead or molding, C.

What I claim as my invention is—

The design for a non-conducting platform, composed of concentric beads or corrugations A A', flat or plain portions B B', and a return-molding, C, substantially as herein set forth.

HENRY L. PALMER.
